[57] ABSTRACT

The invention relates to 7-(2-[1-(phenyl or substituted phenyl-sulfonyl)-2-pyrrolidinylthio]-acetamido)cephalosporanic acids as anti-bacterial agents and the intermediate [1-(phenyl- or substituted phenyl-sulfonyl)-2-pyrrolidinylthio]acetic acids employed in their production.

3 Claims, No Drawings

7-(2-[1-(PHENYLSULFONYL)-2-PYRROLIDINYLTHIO]ACETAMINO)CEPHALOSPORANIC ACIDS

DESCRIPTION OF THE INVENTION

In accordance with this invention there is provided a group of 7-(2-[1-(phenyl- and substituted phenylsulfonyl)-2-pyrrolidinylthio]acetamido)cephalosporanic acids and salts of the formula

in which

R is a member selected from the group consisting of —H, alkyl of 1 to 3 carbon atoms, halo, nitro, alkanoylamido of 2 to 6 carbon atoms and trifluoromethyl.

The intermediate carboxylic acids are prepared by reacting a thioglycolic acid with an appropriately substituted N-(4,4-diethoxybutyl)benzene sulfonamide in the presence of a catalytic amount of a mineral acid, thusly

in which

R is a member selected from the group consisting of —H, alkyl of 1 to 3 carbon atoms, halo, nitro, alkanoylamido of 2 to 6 carbon atoms, and trifluoromethyl;

R² is a member selected from the group consisting of —H and alkyl of 1 to 3 carbon atoms;

R³ is a member selected from the group consisting of —H, alkanoyloxy of 2 to 6 carbon atoms,

The intermediate carboxylic acid is coupled with the 7-aminocephalosporanic acid derivative by either the dehydrative coupling or mixed anhydride technique commonly employed in the production of amide linkages as in the field of polypeptide production. The free carboxyl group of the 7-aminocephalosporanic acid derivative may be converted to a salt (e.g. alkali metal, ammonium or trialkylamine) before or after the coupling reaction by techniques well known in the art.

taken with the 5-carboxy group, —CH2-COO—

or when

The preferred anti-bacterial agents of this invention from the standpoint of production economics are those of the formula:

in which

R is a member selected from the group consisting of —Cl, —Br and —NO₂;

R³ is a member selected from the group consisting of

—H and acetoxy; and

M is a member selected from the group consisting of —H, sodium and potassium.

The cephalosporin derivatives of this invention have been found to be active anti-bacterial agents effective against gram-positive and gram-negative test organisms as well as penicillin resistant staphylococcus, in the well known and scientifically accepted agar serial dilution testing procedure. Thus, the cephalosporin derivatives of this invention are useful in the fields of comparative pharmacology and in microbiology and for the treatment of bacterial infections amenable to treatment with penicillin and cephalosporin derivatives. The intermediate carboxylic acids of this invention are useful for the preparation of the disclosed anti-bacterial cephalosporin derivatives.

The following examples illustrate the preparation of representative intermediate carboxylic acids and representative cephalosporanic acid derivatives of those carboxylic acid reactants. The cephalosporanic acid alkali metal salts were recovered in each instance, the free carboxylic acids being readily produced by known methods. The small amount of residual solvent present in some of the products exemplified is readily removed, if desired by vacuum stripping. The activity of each of the cephalosporin derivatives is provided for the specific bacterial strains against which the compound exemplified was active at or below 250 micrograms per milliliter. The representative nature of the bacterial strains employed to demonstrate anti-bacterial activity are indicative of the broader applicability of the compounds of this invention in the control of bacterial infestations other than those specifically referred to in each of the following examples:

NE CA	<i>Neisseria catarrhalis</i>
BA SU	<i>Bacillus subtilis</i>
BO BR	<i>Bordetella bronchiseptica</i>
ES CO	<i>Escherichia coli</i>
SA PA	<i>Salmonella paratyphi</i>
KL PN	<i>Klebsiella pneumoniae</i>
ST AU	<i>Staphylococcus aureus</i>

EXAMPLE I

[1-(p-Bromophenylsulfonyl)-2-pyrrolidinylthio]acetic Acid

p-Bromo-N-(4,4-diethoxybutyl)benzene sulfonamide (3.8 grams, 0.01 milliliter) and thioglycolic acid (1.0 gram) were dissolved in dimethoxyethane and the solution was heated on a steam bath, in the presence of a few drops of 6N HCl solution for 3 hours. After removal of the solvent, the residue was dissolved in benzene. The benzene solution was extracted with a dilute NaHCO₃ solution and extracted several times with benzene. The benzene extracts were dried over anhydrous MgSO₄. After the benzene was removed, the residue was recrystallized from a mixture of diethyl ether and pentane to afford the title compound, m.p. 86°-89°C.

EXAMPLE II

[1-(p-Acetamidophenylsulfonyl)-2-pyrrolidinylthio]acetic Acid.

The title compound (m.p. 147°-149°C. from CH₃CN) was prepared by a similar procedure to that described in Example I except that p-acetamido-N-(4,4-diethoxybutyl)benzene sulfonamide was utilized at room temperature.

10

Elemental Analysis for C₁₁H₁₈N₂O₅S₂:
Calc'd: C, 46.91; H, 5.06; N, 7.82.
Found: C, 46.94; H, 5.09; N, 8.32.

15

EXAMPLE III

[1-(p-Nitrophenylsulfonyl)-2-pyrrolidinylthio]acetic Acid.

The title compound (m.p. 135°-138°C. from benzene) was prepared by a similar procedure to that described in Example I except that p-nitro-N-(4,4-diethoxybutyl)benzene sulfonamide was utilized at room temperature.

25

Elemental Analysis for C₁₂H₁₄N₂O₅S₂, 1/12C₆H₆:
Calc'd: C, 42.54; H, 3.14; N, 7.94.
Found: C, 42.94; H, 4.26; N, 8.05.

30

EXAMPLE IV

7-(2-[1-(p-Bromophenylsulfonyl)-2-pyrrolidinylthio]acetamido)cephalosporanic Acid.

To [1-(p-bromophenylsulfonyl)-2-pyrrolidinylthio]acetic acid (0.76 gram, 2 millimole) in 4 milliliter dimethylformamide was added carbonyl diimidazole (0.32 gram, 2 millimole) in one portion. The mixture was stirred under nitrogen atmosphere for ½ hour and under vacuum for ½ hour. To the above solution in an ice bath was added a cold solution of 7-aminocephalosporanic acid (0.56 gram, 2 millimole) and triethylamine (0.20 gram) in methylene chloride. The solution was stirred in an ice bath for 1 hour and at room temperature for 1 hour. Some insoluble material was filtered off. The filtrate was evaporated under reduced pressure at approximately 30°C. To the residue dissolved in methylene chloride was added one milliliter of a 2M potassium 2-ethyl hexanoate. Addition of anhydrous diethyl ether caused precipitation of a salt, which was collected, washed with diethyl ether and dried.

60

EXAMPLE V

7-(2-[1-(p-Nitrophenylsulfonyl)-2-pyrrolidinylthio]acetamido)cephalosporanic Acid.

Elemental Analysis for C₂₂H₂₂BrN₃O₅S₂:
Calc'd: C, 37.89; H, 3.71; N, 3.68.
Found: C, 38.05; H, 3.92; N, 3.74.

65

The title compound was prepared by a procedure similar to that described in Example IV except that [1-(p-nitrophenylsulfonyl)-2-pyrrolidinylthio]acetic acid was utilized.

Elemental Analysis for $C_{22}H_{23}N_4O_{10}S_3K\frac{1}{2}(C_2H_5)_2O\cdot 1\frac{1}{2}H_2O$:

Calc'd:	C, 40.36; H, 4.20; N, 8.19.
Found:	C, 40.12; H, 3.67; N, 8.25.

ST AU	CHP .976
ST AU	53-180 .976

What is claimed is:

1. A compound of the formula:

in which

R is a member selected from the group consisting of H, Cl, —Br and —NO₂;

R³ is a member selected from the group consisting of —H and acetoxy; and

M is a member selected from the group consisting of —H, sodium and potassium.

5 10 2. The compound of claim 1 which is 7-(2-[1-(p-bromophenylsulfonyl)-2-pyrrolidinylthio]acetamido)cephalosporanic acid.

15 3. The compound of claim 1 which is 7-(2-[1-(p-nitrophenylsulfonyl)-2-pyrrolidinylthio]acetamido)cephalosporanic acid.
